UNITED STATES PATENT OFFICE.

WARREN G. SLATER AND JEREMIAH LAMOREAUX, OF FREMONT, MICH.

BUTTON-ATTACHING MACHINE.

SPECIFICATION forming part of Letters Patent No. 339,337, dated April 6, 1856.

Application filed January 23, 1856. Serial No. 189,515. (No model.)

To all whom it may concern:

Be it known that we, WARREN G. SLATER and JEREMIAH LAMOREAUX, both citizens of the United States, residing at Fremont, in the 5 county of Newaygo, State of Michigan, have invented certain new and useful Improvements in Button-Attaching Machines, of which the following is a specification, reference being had therein to the accompanying drawings.

10 This invention has relation to certain novel improvements on machines for fastening buttons to clothing, shoes, and other articles, which improvements will be fully understood from the following description, when taken in connection with the annexed drawings, in which—

15 Figure 1 represents a side view of our device. Fig. 2 is a front view of the same. Fig. 3 is also a side view, the reverse side to that shown in Fig. 1, with tube removed. Fig. 4 is 20 a detail view. Fig. 5 also a detail view. Figs. 6 and 7 are cross-sections of the tube, the former taken on line *y y*, Fig. 2, and the latter on line *x x*; and Fig. 8 is a perspective view of the tube.

25 Referring by letter to the accompanying drawings, *A* designates the base of the main frame of the machine, and *B* a standard rising perpendicularly from and rigidly secured to or east with said base, and *C C'* are horizontal arms or guides which are rigid with said stand- 30 ard *B*. The base *A* is designed to be secured to a table, and the working parts of the machine to be operated by the foot of an attendant acting on a treadle.

35 *D* designates a vertically-reciprocating bar, which passes freely through the base *A* and through the arms *C C'*, and is suitably connected at its lower end to the treadle above referred to.

40 To the end of a right-angular extension, *C²*, of the reciprocating bar *D* a jaw-stock, *E*, is suitably pivoted, which, together with a smaller jaw-stock, *E'*, passes freely through and is guided by the horizontal arms *C C'*. The said jaw-stocks are depressed by the attendant acting 45 on the treadle, and they are caused to rise quickly by means of a spring, *F*, one arm of which is secured upon the lower arm, *C*, and the other arm is attached to the staple fixed to the jaw-stock *E*. The peculiarity of the gripping jaws *a a'* on the lower ends of the said stocks will be presently described.

50 The lower end of the jaw-stock *E'* and its jaw

is caused to separate from the jaw *E* at the commencement of the ascending strokes of both jaws by means of the interposed spring *b*, and 55 the jaw *E'* is beveled on its back at *b'*, so that at the commencement of each descending stroke of this jaw the said beveled surface will impinge against the point *b²* on the arm *C'* and cause the jaw *a'* to firmly grip a button and its fastener, as indicated in the drawings. The button *c*, with its fastener *c'*, is firmly gripped between the jaws *a a'* until the operation of clinching the fastener to a piece of cloth or leather is effected. 60

65 The jaw-stock *E'* is provided near its upper end with a stud, *e*, which has a limited vertical movement in a recess, *e'*, formed in the back edge of the jaw-stock *E*. By this means the jaw-stock *E'* is caused to rise and fall with the 70 jaw-stock *E*, and the jaw *a'* is allowed to accommodate itself to the neck of a button and to the fastener thereof, both of which are linked together, as shown in the drawings, before they are introduced into a feeding-tube, *G*, herein-after described. The opposing sides of the 75 jaws are scored out at *f*, to receive freely the button-heads, one at a time, and the gripping portions of the jaws are rabbeted at *f' f'*, for the purpose of firmly gripping the neck of a 80 button, and also the peculiar-shaped button-fastener, as shown in the drawings.

85 The feeder *G* for the buttons and their attached fasteners consists of an inclined straight tube having a guide-pin, *g*, extending its entire length on one side of a longitudinal slot, *g'*, also extending the entire length to the said tube along its bottom, and serves to keep the button-eyes and the hanging fasteners in proper position for delivery between the gripping jaws *a a'*. This feeder *G* is held in proper relation to the gripping-jaws by means of an inclined sheath, *H*, which is secured to the lower arm, *C'*, as shown, from which sheath the feeder is readily removable for resupplying it 90 with buttons and fasteners from time to time. The buttons and their fasteners are fed by their own gravity to the jaws *a a'*, when these jaws are at the terminus of the ascending strokes. 95

100 On the rear side of the feeding-tube *G* is a long leaf-spring, *J*, the lower end of which terminates near the beveled discharge end of said tube, and is adapted to be pressed backward

by a spring-arm, K, fixed to the back of the gripping-jaw a' . On the upper edge of the spring J are formed two small stops and releasing devices, $h h'$, which enter freely through the wall of the tube G and arrest the descent of the buttons. When the empty jaws $a a'$ are suddenly thrown up by the spring F, the arm K will strike the free end of the spring J and allow one button, with its fastener attached to it, to escape the stops $h h'$ and descend between said gripping-jaws $a a'$. Directly below the jaws $a a'$, and secured to the base A of the machine, is an anvil, L, having a transversely-grooved surface, i, upon which the spurs or points of the fasteners are bent and clinched to the cloth or leather.

The device for regulating the feed or flow of buttons to the gripping-jaws may be applied on top of the feeding-tube, if desirable.

Having described our invention, what we claim is—

1. In a button-fastening machine, the combination, with the main guide-frame, of gripping-jaws formed, as described, on vertically-movable stocks, the spring-actuated stock E', independently movable of the stock E, and also movable with it, and the means, as described, for causing the jaw a' to close and grip a button and its fastener, substantially as described.
2. The combination, with the vertically-movable angular guide, as described, of the jaw-stock E, pivoted to this bar, the jaw-stock E', having a limited vertical movement independently of the stock E, and also vertically movable with it, the spring between the jaw-stocks, and the closing bevel on the stock E, substantially as described.
3. The combination, with the main frame,

constructed as described, of the jaw-stocks recessed and rabbeted, and provided with the spring b' , pin e , and recess e' , and the stock E', having the inclined surface b on its rear side, adapted to operate upon the beveled surface b' of the arm C, whereby the two jaws are brought together in their downward stroke, thereby gripping the fastener and button, as described, and for the purpose specified.

4. In a button-attaching machine, the combination, with the gripping-jaws and clinching-anvil, as described, of the inclined feeding-tube having the slot g' and guide-ping, arranged vertically and running parallel with said slot, the spring J, provided with the releasing points or stops $h h'$, entering the perforations in the tube, and the arm K, secured to the jaw-stock a , the whole adapted to operate as described, and for the purpose specified.

5. In a machine for fastening buttons to cloth or leather, the combination of the following elements: the main guide-frame, the gripping-jaws and their stocks, actuated as described, a feed-tube, a sheath therefor, from which the tube is removable, a device for regulating automatically the feed of the buttons with their fasteners attached to the said gripping-jaws, and an anvil for clinching the fasteners, all constructed and adapted to operate substantially in the manner and for the purposes set forth.

In testimony whereof we affix our signatures in presence of two witnesses.

WARREN G. SLATER.
JEREMIAH LAMOREAUX.
